UNITED STATES PATENT OFFICE

157,106

RADIATION MEASURING INSTRUMENT

John A. Victoreen, Cleveland, Jeffrey M. Bevis,
East Cleveland, Arthur F. Bush, Cleveland, and
Richard D. Kidney, Parma Heights, Ohio

Application June 19, 1948, Serial No. 147,084

Term of patent 14 years

(Cl. D52—1)

To all whom it may concern:

Be it known that we, John A. Victoreen, a citizen of the United States, and resident of Cleveland, in the county of Cuyahoga, State of Ohio, and Jeffrey M. Bevis, a citizen of the United States, and resident of East Cleveland, in the county of Cuyahoga, State of Ohio, and Arthur F. Bush, a citizen of the United States, and resident of Cleveland, in the county of Cuyahoga, State of Ohio, and Richard D. Kidney, a citizen of the United States, and resident of Parma Heights, in the county of Cuyahoga, State of Ohio, have invented a new, original, and ornamental Design for a Radiation Measuring Instrument, of which the following is a specification, reference being had to the accompanying drawings, forming a part thereof.

Fig. 1 is a side elevational view of a radiation measuring instrument, showing our new design;

Fig. 2 is a plan view thereof; and
Figs. 3 and 4 are elevational views from opposite ends thereof.

The opposite side from that illustrated in Fig. 1 is the same.

We claim:

The ornamental design for a radiation measuring instrument, as shown and described.

JOHN A VICTOREEN.
JEFFREY M. BEVIS.
ARTHUR F. BUSH.
RICHARD D. KIDNEY.
